UNITED STATES PATENT OFFICE.

EDWARD S. MARKS, OF AUBURN, NEW YORK, ASSIGNOR TO OHIO TOOL COMPANY, OF AUBURN, NEW YORK, A CORPORATION OF NEW YORK.

FOLDING SQUARE.

No. 864,011.

Specification of Letters Patent.

Patented Aug. 20, 1907.

Application filed March 18, 1907. Serial No. 363,038.

To all whom it may concern:

Be it known that I, EDWARD S. MARKS, a citizen of the United States, residing at Auburn, in the county of Cayuga and State of New York, have invented or discovered certain new and useful Improvements in Folding Squares, of which the following is a specification, reference being had therein to the accompanying drawings.

The present invention relates to folding squares and 10 has for its object to provide a square of economical and practical construction which is adapted to be folded into a comparatively small space in order that the same may be conveniently carried in the pocket or placed in a small chest, and which when set for use is 15 as rigid and accurate as an ordinary solid square.

To accomplish this and other objects my invention comprises two arms or members pivotally connected in such a manner as to permit them to be swung into a position of parallelism, or to be swung apart and set in a 20 position perpendicular to one another, together with a releasable locking device of new and improved construction adapted to lock said members rigidly in their set position or at right angles to each other.

One construction in which my invention may be embodied is illustrated by the accompanying drawings, in which:—

Figure 1 is a view of the square locked in its set or open position. Fig. 2 is a similar view with the locking device released. Fig. 3 is a view of the square folded, and Fig. 4 is a section taken substantially on the line 4—4, Fig. 1.

As shown in the drawings, the square comprises two arms or members, 12 and 13, respectively, pivotally connected by means of a web 14 formed upon or attached to the member 12 and adapted to enter a groove 15 formed in the edge of the member 13, and a pivot 16 passing through the member 13 and the web 14. Preferably, also, the member 12 is provided with a tongue 17 adapted to enter the groove 15 in the member 13, thus contributing to the lateral strength and rigidity of the device as a whole.

The member 12 is provided with a short arc-shaped slot 18 formed concentric with the pivot 16, said slot terminating in an enlarged recess or opening 19 providing a locking shoulder or shoulders 20, 20. The member 13 is provided with a curved projection or finger 21, also formed concentric with the pivot 16, and adapted, when the arms 12 and 13 are swung toward open or set position, to enter the slot 18 in the member 12. Said projection or finger 21 carries at its end a latch 22 mounted on a pivot 23 whose axis is substantially perpendicular to the axis of the pivot 16, said latch 22 being of substantially the same size and shape as the recess 19 and being adapted to coöperate with

the shoulder or shoulders 20 thereof, thereby securely 55 to lock the arms or members in their set position.

The projection or finger 21 may be formed integral with the member 13, but preferably, and as herein shown, this finger is constructed as a separate piece provided with a tongue 24 entering the groove 15 and 60 fastened therein by means of rivets 25, 25, or equivalent securing devices.

Inasmuch as the axes of the pivots 16 and 23 lie in perpendicular planes, any force tending to move the arms from their set position will have no effect upon the 65 latch 22, tending to release the same, and the square is therefore not liable to be accidentally thrown out of its proper set position. Moreover it will be noticed that the latch 22 is carried on the end of the finger 21, by a pivot whose axis lies in a line substantially intersecting 70 the axis of the pivot 16, so that all forces tending to move the arms upon their pivot 16 will be transmitted to the latch as a direct pull thereon, thus obviating all torsional and other strains tending to twist or otherwise distort the latch. It will furthermore be seen that the 75 locking face of the latch extends across the entire thickness of the member 12 thus providing a very secure and rigid lock, but that, at the same time, the locking device lies wholly within the outline of the pivot 80 arms, and has its flat surfaces substantially flush with the flat surfaces of the arms. It will thus be apparent that when the parts are in their normal or set position there are absolutely no parts projecting beyond the surface or outline of the square, which therefore combines all the advantages of the ordinary solid 85 square with the conveniences incidental to the best types of folding squares.

While I, in order that my invention may be more readily understood, have herein described the same as embodied in a specific construction, it is obvious that 90 many changes may be made in the construction shown without departing from the spirit and scope of my invention.

Having thus described my invention, I claim and desire to secure by Letters Patent:

1. In a device of the character described, the combination with a pair of arms and a pivot connecting said arms, one of said arms having a portion projecting beyond said pivot, of a locking device, and a pivot connecting said locking device to said projecting portion, the axis of said last-named pivot being substantially at right angles to the axis of said first-named pivot.

2. In a device of the character described, the combination with a pair of arms, and a pivot connecting said arms, of a locking device, and a pivot connecting said locking device to one of said arms, the axis of said last-named pivot being substantially at right angles to the axis of said first-named pivot and lying in a line substantially intersecting the same.

3. In a device of the character described, the combination with a pair of arms and a pivot connecting said

arms, of a locking device, and a pivot connecting said locking device to one of said arms, the axis of said last-named pivot lying in a line substantially intersecting the axis of said first-named pivot.

5. 4. In a device of the character described, the combination with a pair of arms and a pivot connecting said arms, of a locking device having a locking surface operative substantially throughout the thickness of one of said arms, and a pivot connecting said locking device to the other of said arms, the axis of said last-named pivot lying in a line substantially intersecting the axis of said first-named pivot.

5. In a device of the character described, the combination with a pair of arms and a pivot connecting said arms, of a locking device adapted, when in operative position, to lie wholly within the outline of said arms, and a pivot connecting said locking device to one of said arms, the axis of said last-named pivot lying in a line substantially intersecting the axis of said first-named pivot.

20. 6. In a device of the character described, the combina-

tion with an arm having an opening therein and an arc-shaped slot communicating with said opening, of a second arm pivotally connected to said first-named arm, a curved finger carried by said last-named arm and adapted to enter said arc-shaped slot, and a locking device pivotally connected to said finger and adapted to enter said opening.

7. In a device of the character described, the combination with an arm having an opening therein and a slot communicating with said opening, of a second arm pivotally connected to said first-named arm, a finger carried by said last-named arm and adapted to enter said slot, and a locking device connected to said finger and adapted to coöperate with said opening.

In testimony whereof I affix my signature, in presence of two witnesses.

EDWARD S. MARKS.
